UNITED STATES PATENT OFFICE.

SAMUEL G. BUSKARD, OF HAMILTON, ONTARIO, CANADA, ASSIGNOR TO THE
MANUTIL CORPORATION, OF BROOKLYN, NEW YORK, A CORPORATION OF
NEW YORK.

PRESSING-IRON.

1,384,301.

Specification of Letters Patent. Patented July 12, 1921.

Application filed August 19, 1919. Serial No. 318,525.

To all whom it may concern:

Be it known that I, SAMUEL G. BUSKARD, a subject of the King of Great Britain, and resident of the city of Hamilton, county of 5 Wentworth, Province of Ontario, in the Dominion of Canada, have invented certain new and useful Improvements in Pressing-Irons, described in the following specification and illustrated in the accompanying 10 drawings, that form part of the same.

The principal objects of this invention are, to facilitate the work of pressing textile fabrics by distributing steam to the face of the iron as it is being used and to generate 15 the steam within the iron as required.

A further object is to devise an electrically heated iron which will utilize the heat produced to best advantage in its distribution through the ironing surface.

20 A further and important object is to simplify the construction thereby producing an iron which may be manufactured at very low cost, and to provide an iron which will greatly reduce the danger of burning the 25 fabrics.

A still further object is to devise a construction in which a low heat may be maintained when the iron is not in constant use but which will produce a high heat when 30 required.

The principal features of the invention consist in the novel construction and arrangement of parts, whereby an electric heating element is secured between and in 35 contact with the base of the iron and a steam generating chamber, and whereby steam is fed to the face of the iron and to a steam chamber arranged between the heating element and the ironing face and whereby the 40 electric heating element is divided into two sections and a switch is arranged to connect either of said sections with the electric current supply.

In the drawings, Figure 1 is a longitudinal mid-sectional view through my improved iron.

Fig. 2 is a top plan view of the iron with the handle removed showing the arrangement of the surface steam distributing channels in dotted lines.

Fig. 3 is a vertical sectional view through a portion of the iron and through the water control valve.

Fig. 4 is a cross sectional view of Fig. 1. 55 The base 1 of the iron is preferably cast

with a flat recess 2 extending practically from end to end and side to side thereof and below this recess is arranged a pair of channels 3 which unite at the point end of the iron and are connected together at the back 60 end by a cross channel 4.

Small holes 5 are bored through the face of the iron communicating with these channels and forming steam outlets.

An electric element 6 is located upon the 65 upper face of the base 1 and over this is placed an insulating plate 7. A second electric element 8 is placed on top of the plate 7.

A hollow casting 9 rests upon the upper 70 electric element being suitably insulated therefrom and forms a holding plate to retain the electric elements tightly in contact.

The upper element is preferably made of a greater heating capacity than the lower electric element and a pair of contact posts 75 10 are secured to and insulated from the member 9 and electrically connected with the upper element 6.

A pair of contact posts 11 are secured to the plate 7 and electrically connected with 80 the element 8. The upper ends of these posts are slotted and the slots of one set of posts are arranged in alignment with the other set of posts.

A casing 12 secured to the base of the iron 85 incloses the hollow member 9 and the electric elements and upon the rear end of this casing are mounted a pair of rigid contact pins 13. These are insulated from the casing and upon the inner ends thereof are 90 mounted the swinging switch arms 14 which are adapted to engage the slotted contact posts 10 or 11 according to the position in which they are swung. The switch arms are connected together by an insulating cross 95 bar 15 and to this cross bar is connected a link 16.

The handle 17 of the iron is secured to the handle frame 18 which is rigidly connected to the casing 12 and the rear lug 19 of the 100 frame is slotted longitudinally and at the upper end is provided with a pair of lugs 20 between which is pivotally mounted a lever 21.

The lower end 22 of the lever extends 105 downwardly through a slot 23 in the casing 12 and is pivotally connected to the link 16. The forward end of the lever 21 forms the under part of the handle. A coil spring 24 arranged in the forward part of the upper 110

portion of the handle forces the lever downwardly so as to swing the switch arms 14 into contact with the posts 11 of the lower element and when the lever is swung upwardly against the pressure of the spring 24, the switch arms 14 are swung clear of the contact posts 11 and move into engagement with the contact posts 10, thereby directing the current through the high heat element. 5 If desired the switch may retain contact with the low heat when the high heat is on.

A latch member 25 is pivotally secured in the forward end of the lever 21 and is adapted to lock the lever in the raised position. 15 The recess 2 and channels 3 are connected with the chamber formed in the hollow casting 9 by means of a tube 26 and is adapted to convey steam from the hollow casting to 20 said chamber and channels.

A water pipe 27 is connected to a valve chamber 28 which is secured in the member 9 having a small tube 29 extending inwardly practically to the center of the chamber 25 within the member 9.

A valve 30 closes the water passage and is provided with a coarse threaded portion 31 and upon rotation in one direction lifts the valve from its seat.

30 A lever 32 is connected with the upper end of the spindle of the valve and to the end of this lever is connected a link 33 extending across the top of the iron having its other end connected to one end of the lever 35 34, the latter lever being arranged parallel to the handle 17 so that the operator may readily swing it upon its pivot to open or close the water supply to the steam generating chamber.

40 In the operation of this device, when the iron is not in active use but is connected up with the electric wires the rotatable switch arms 14 are, by reason of the connections herein described effected by the action of the 45 spring 24 in the handle, held in contact with the posts 11 thereby connecting the low heat element. This maintains the temperature of the iron at a moderate heat.

When the iron is taken up for active use 50 the act of gripping the handle swings the lever 21 on its pivot and changes the position of the switch arms 14 to connect with the contact posts 10, thereby connecting up the high heat element. This element is arranged immediately beneath the hollow casting 55 9 into which the water is introduced through the small tube 29 when the valve 30 is opened and steam is created within the chamber at a high temperature. The steam 60 finds its way through the tubes connecting the recess 2 and channels 3 therewith and the face of the iron is heated by the steam temperature. This steam heating of the face 65 of the iron reduces the tendency of burning and the direct application of steam to the

face of the iron, while it is not new, is applied in conjunction with the other features.

It is important to note that the heat of the electric elements is absorbed by the steam chambers which conduct the heat to 70 the desired portion of the iron, thus avoiding too high a temperature on the face of the iron which will prevent burning. The electric switch may be held closed in the high heat position by operating the latch 75 member 25 and when the iron is set aside temporarily the latch may be released to release the switch.

An iron constructed as described is extremely simple and very effective in use. 80

What I claim as my invention is:

1. A pressing iron comprising, a base having steam passages leading to the face, a two element electric heater secured to said base, a hollow casing secured against said heater, means for conducting steam from said hollow casing to said steam passages, and means for directing electric current to either element of said heater. 85

2. A pressing iron comprising, a base having steam passages leading to the face, an electric heater element arranged on top of said base, an insulating plate covering said element, an electric heater element arranged on top of said insulating plate and having 90 a greater resistance than the lower one, a hollow casing arranged above the upper element and clamped thereagainst, means for directing an electric current to the lower element to maintain a low heat, means for 95 shifting the electric current connection to the upper element to obtain a high heat, means for feeding water to the hollow casing, and means for conducting steam from said casing to the steam passages. 100

3. A pressing iron comprising, a base having steam passages leading to the face, a two-element electric heater secured to said base, a hollow casing secured against said heater, means for conducting steam from said hollow casing to said steam passages, a switch adapted to connect either element of said heater with the electric current, a lever supported from the iron handle, operatively connected with said switch, and spring 110 means for holding said switch in contact with one portion of said heater element. 115

4. A pressing iron comprising, a base having steam passages leading to the face, a two-element electric heater secured to said 120 base, a hollow casing secured against said heater, means for conducting steam from said hollow casing to said steam passages, electric contacts arranged on each of the elements of said heater, pivotal switch arms 125 adapted to coöperate with said contacts, a handle on said iron, and a lever connected with said pivotal switches and supported from said handle.

5. A pressing iron comprising, a base hav- 130

- ing steam passages leading to the face, a two-element electric heater secured to said base, a hollow casing secured against said heater, means for conducting steam from 5 said hollow casing to said steam passages, electric contacts arranged on each of the elements of said heater, pivotal switch arms adapted to coöperate with said contacts, a handle on said iron, a lever arranged beneath said handle and pivoted at one end thereof and having a downward extension, a link connected with the downward extension of said lever and with said pivotal switch arms, and a spring arranged on said 10 handle adapted to engage the lever and hold the switch arms in engagement with one of the elements of said heater.
6. A pressing iron comprising, a base having steam passages leading to the face, an 15 electric heating element secured to the upper side of said base, a plate covering said element, a second heating element arranged on said plate, a hollow casing secured on top of said second element, contact posts secured to said plate and electrically connected with 20 the lower heating element, contact posts secured to said casing and electrically connected with the upper heating element, a cover secured to said base and extending over said casing, a pair of contact posts secured to 25 said cover, pivotal switch arms secured to said cover posts and adapted to engage the posts of either of said heating elements, a link connected to said switch arms, a handle secured to said cover, a crank lever connected to said link and pivotally supported from 30 said handle, and a spring arranged in said handle and engaging said lever.
6. A pressing iron comprising, a base having steam passages leading to the face, an 35 electric heating element secured to the upper

SAMUEL G. BUSKARD.
